FASTENER

Filed Oct. 4, 1922

UNITED STATES PATENT OFFICE.

ERNEST S. JOHNSON AND ERIC V. CARLSON, OF BROCKTON, MASSACHUSETTS, AS-SIGNORS TO GENERAL FASTENER COMPANY, OF BROCKTON, MASSACHUSETTS, A CORPORATION OF MASSACHUSETTS.

FASTENER.

Application filed October 4, 1922. Serial No. 592,412.

To all whom it may concern:

Be it known that we, ERNEST S. JOHNSON and ERIC V. CARLSON, citizens of the United States, and residents of Brockton, in the 5 county of Plymouth and State of Massachusetts, have invented an improvement in Fasteners, of which the following description, in connection with the accompanying drawings, is a specification, like letters on 10 the drawings representing like parts.

Our present invention consists in a novel and improved method of interchangeable fasteners, as well as an improved fastening apparatus.

15 Broadly considered, our invention consists in the provision of devices which will enable different sets of colored, designed or series of buttons, studs, ornaments for apparel or the like to be utilized on the same 20 fastening members. Thus we contemplate the provision of fastening members, suitable for application to a suit, shirt waist, or other apparel, having permanently secured thereto a portion of the fastener members 25 and having provision for detachably securing thereto the finished portions consisting in varying sets of the finished buttons, differing in color, if desired, differing in design and material suitable for matching with 30 other garments. Our invention can be applied, for example, to a lady's shirtwaist, wherein the fastener elements are secured to each side of the garment and with a removable set of blue buttons, red buttons, or 35 other ornamental and useful designs, thus enabling any one of a series of such sets to be used on the fasteners, in accordance with the choice or wish of the wearer, and thereby enable the garment having the fastener to be fitted with ornamental finished buttons, which in appearance will match 40 with any other desired garment. Also this interchangeability of different sets of finished portions, for the buttons and fasteners, 45 will enable the wearer to change the same garment for matching with the different colored garments by a suitable shifting of the interchangeably finished buttons.

A further feature of our present invention relates to the fastener devices having capability for uniting a plurality of layers in the same plane and by means of interrelating fastener devices. Thus we contemplate the utilization of a fastener member which will be permanently secured to one layer, a co-operating fastener member permanently secured, if desired, to a second layer, and means to unite a third layer thereto, and so on to an indefinite plurality if desired, and all on the same cooperating fasteners. 50 Thus for example it is frequently desirable, particularly in wearing apparel, to have garments with a plurality of overlapping portions, and our invention contemplates the uniting of all said plurality of overlapping portions, three or four, on the same line of 55 fasteners and in the same position, whereas heretofore only two layers could be united at the same point and with the same fasteners, a plurality of fasteners at spaced points 60 being necessary to unite three or more such layers. While our invention contemplates the utilization of the features above briefly outlined, and particularly with relation to apparel, garments, ladies' shirtwaists, suits, 65 etc., it will be appreciated that the invention is not so limited but has a large field of usefulness in connection with other arts, fastening automobile tops, waterproof casings, coverings and the like.

70 We believe that the provision of a multiplicity of fastener elements capable of uniting a plurality of three or more layers together at the same point and based on the same fastener elements, is distinctly new 75 and we wish to claim the same broadly. We are also advised that the arrangement of interchangeability for series or sets of different colored buttons, in combination with a fastener element or elements, is distinctly 80 new, and we wish to claim this feature broadly.

85 While we may utilize any suitable type of fasteners in carrying out our said inventions, we prefer to employ the fastener illustrated 90 and described herein, which contains certain 95

novel features and is of special usefulness and adaptability to the interchangeable button feature as well as to that of uniting a plurality of pairs of layers. This fastener 5 comprises a socket member suitable for permanent attachment to one layer, an intermediate member suitable to be snapped into the socket member and also capable of being attached to a second layer with a portion 10 adapted to be united with a third fastener element. This latter element may be one of the series of interchangeable buttons, if desired, and may be of sufficient size to overlap and hold a third layer or may itself 15 be attached to a third layer.

Referring to the accompanying drawings, wherein we have illustrated two forms of fastener and interchangeable finished button member,

20 Figs. 1, 2, and 3 are cross-sectional views respectively of one form of fastener having the interchangeable finished button, the intermediate fastening element, and the first fastener member respectively;

25 Figs. 4, 5, and 6 are respectively a finished button, intermediate member, and base fastener of a second form in cross-section;

Fig. 7 illustrates, also in cross-section, the 30 set of fastener elements of Figs. 4, 5, and 6 united in position;

Fig. 8 is a horizontal cross-sectional view on the line 8—8 of Fig. 6;

Fig. 9 is a cross-sectional view of the 35 finished or colored button portion which may be of celluloid or any other suitable or desirable material;

Fig. 10 illustrating the method of uniting the finished button portion of Fig. 9 to the topmost fastener element.

40 Referring to the fastener illustrated in Figs. 1, 2, and 3, the outer, upper or finished button member is illustrated at Fig. 1, and is designated generally at 1. This button comprises an inner flanged shell 2 in circular form, with a central socket portion 3 struck up therein, having a pair of grooves or recesses 4, 4, cut in the shank part 5 to receive the end portions 6, 6, of a spring 10, the latter having its main part housed 45 against the flange 2 of the shell and maintained in position by curving over the edge 7 of the flange of said shell or body portion 2. This construction forms the socket member of the fastener herein illustrated, 50 Fig. 1 showing same for the topmost or outer button and Fig. 6 illustrates the same for the lowermost socket when the form of 55 Figs. 4, 5, and 6 is utilized.

Attached to the shell or body portion 2 60 as above described, is the finished element 12, preferably in the form of a concavo-convex button surface and of any suitable or desirable material and finish, color or design. This element 12 may be of metal, silver, bronze, pearl or other jewelry and

suitably engraved, embossed or finished, or may be and preferably is of celluloid or the like material, being colored in such shades and of such appearance as will be suitable for the use to which it is applied. By having 70 a series or set of different colored elements 12 for the buttons, the manufacture of our fasteners with a plurality of sets of colored buttons for interchangeable attachment, is readily and economically accomplished. 75 This element 12 may be applied in any desired manner, but we prefer to secure the same firmly to the button portion, for this purpose utilizing a ring 15 (see Fig. 10) and turning in the edge portions 16 and 17 80 of this ring upon the marginal edge of the element 12 and of the shell or body member 2 as clearly shown in Figs. 1 and 10. The combined button and fastener thus described can be utilized either as an interchangeable finished member for our invention, and for this purpose may be attached to and detached from as well as replaced and renewed, with other colored or finished buttons, independently of any attachment 90 to cloth or a layer of material. Or it may be utilized to simply button over and secure by overlapping a third layer. Or it may itself be attached if desired. For the latter purpose we provide a plurality of 95 perforations 18, 18, 18, 18, for such being here shown, through which the button may be secured by sewing, clamping or the like to a layer of material.

To cooperate with the button as thus far 100 described, we provide an intermediate fastener member consisting in the plate or body portion 20 and stud 21, the latter of suitable form, length and size to fit within the socket 3 and having a neck 22 arranged to 105 snap by and thereafter be secured by the end portions 6, 6 of the spring 10. This second fastener element 20 is also provided with a plurality of perforations 23, 23, to be sewed, stitched or otherwise secured to 110 a layer of cloth. In order to make this member also a cooperating detachable fastener element, we provide a pair of recesses 24, 24, through one portion of the neck 22, and fit within the body portion 20 a 115 spring 25, having its end portions 26, 26, corresponding with the end portions 6, 6, of the spring 10 already described. This spring is retained within the member 20 120 by its normal expansibility and the turning over of the edge portion 27 thus affording a marginal recess therefor. To cooperate with the intermediate fastener 20 just described, a third fastener element 30 is arranged, having a stud 31 adapted to fit within a combined stud and socket member 21 of the intermediate fastener 20, the neck portion 32 being arranged to "snap" by the spring ends 26 in the same manner as that already 125 described. Perforations 33, 33, through 130

this fastener element 30 also enable it to be secured to a layer of cloth or other material. The cooperating fastening members thus described comprise means to unite two or 5 more layers of cloth together, such for example as the meeting edges of a lady's suit, shirtwaist, or the like, and in addition to this fastening feature, enable a third layer to be secured by the button 1 as well as enabling 10 a series or sets of such buttons 1 to be interchangeably secured at will to the garment having the fastener elements 20 and 30 permanently attached to the margin portions. This construction is illustrative 15 only of our invention of means to provide an instant interchangeability of the finished portions of fastener elements and it will be appreciated that we may utilize any type, style or method of fastening instrumentalities, it being possible to carry out our invention in a large number and variety of 20 devices.

As shown in Fig. 7, we have illustrated a modified form of fastener, wherein a plurality of socket members similar to the fastener portion of the button member, as illustrated and described in Figs. 1 and 6, is employed. In this form we utilize the button portion consisting in the shell or 25 body part 2, socket portion and spring for both the bottom or base fastener device and for the top or button carrying arrangement. In this modification it will be noted that both the top portion and the bottom portion, i. e., the fastener devices with the bottom arranged in inverted position, present 30 two cooperating socket members, the same being illustrated at Figs. 4 and 6. Therefore we provide an intermediate member as shown in Fig. 5, with a plurality of stud portions adapted to cooperate with the two socket members 3 in inverted position. As 35 illustrated in Fig. 7 we have designated the topmost fastener portion by the reference character 1, this being identical with the top button already described in the previous set 40 of fasteners, and the bottom fastener member 41, being the same as the top member without the finished button portion 12 and the retaining ring 15. The intermediate fastener member, as shown in Fig. 5, and as 45 illustrated in fastening position in Fig. 7, consists in a plate 44, having thereon a projecting stud 45 and narrow neck 46 to cooperate with the spring end portions 6, 6, this 50 plate 44 having a curved flange 47 adapted to engage the rim 49 of a duplicate plate member 50 having thereon a stud 51 and neck 52 identical in arrangement, size and 55 construction with the stud 45. This intermediate fastener member is adapted to unite the two button portions detachably together, as shown in Fig. 7. We also provide perforations 55, through the plates 44 and 50, 60 to enable this intermediate member to be

attached to a layer of material 56, the lower button in Fig. 7 being secured to a layer 57 and the topmost of upper button 1 either being attached to a third layer 60 or simply retaining the same in position by its overlapping extent. Thus in a coat, jacket, shirtwaist or the like, if the edge portion 57 of one layer has secured thereon one of our fasteners, and the second meeting edge 65 70 75 80 85 90 95 100 105 110 115 120 125 130 our fastener, and the second meeting edge 56 has secured to it a second layer, these two can be attached together in the manner of a usual snap fastener, but with the provision of adding one of the set of buttons constituting a desired finish therefor of any suitable color as may be fancied by the wearer. Also a third layer 60 may be retained. In the form of fasteners shown in Figs. 1, 2, and 3, a greater plurality can be utilized, it being within the scope of our invention to join a considerable number of layers of material at the same point and by the same fastening devices in combination with the detachable, interchangeable and finished button, or not. In the first series, i. e., as shown in Figs. 1, 2, and 3, the bottommost layer of material would be attached to the fastener portion 30 and the second layer to the upper 20, the finished button being then applied if only these two layers were desired, as in the meeting edges of a coat, jacket, shirtwaist or the like.

It will be appreciated that our invention of the detachable, renewable and interchangeable sets or series greatly simplifies the process of shifting or changing buttons or ornaments, the same base and intermediate fastener being at all times united if desired to the garment or material to be fastened and the ornamental part only being interchanged. Furthermore the arrangement as herein shown of securing the ornamental portion 12 by the ring 15 gives a capacity for a still further interchangeability, such rings being readily removed and a different ornamental member 12 being secured if desired.

Our invention is further described and defined in the form of claims as follows:

1. An attachable and detachable fastener comprising a member, a projecting head arranged on one face thereof, a second member provided with a socket arranged on one face thereof, a third member, arranged intermediate the first and second members, and a combined projecting head and socket member arranged on one face thereof, the projecting head of the first member adapted to fit within the socket of the third member and the projecting head of the third member adapted to fit within the socket of the second member.

2. An attachable and detachable fastener comprising a member, a projecting head arranged on one face thereof, a second member provided with a socket arranged on one

face thereoff, a third member arranged intermediate the first and second members, and a combined projecting head and socket member arranged on one face thereof adapted to fit within the socket of the third member, the projecting head of the third member adapted to fit within the socket of the sec-

ond member, a colored ornamental member, and means for removably attaching the same to the second member. 10

In testimony whereof, we have signed our names to this specification.

ERNEST S. JOHNSON.
ERIC V. CARLSON.
